METHOD AND APPARATUS FOR INCREASING THE LIFT OF AIRPLANES

Application filed June 25, 1930. Serial No. 463,802.

This invention relates to improvements in airplanes and more particularly has reference to a method and means for increasing the lift factor of airplanes.

A considerable effort has been expended to increase the lift effect on airplane wings, as its desirability has long been recognized. At the present, the advantage to be gained from a short distance take-off and a relatively low landing speed, so that the plane may land in small spaces are still being sought. Methods proposed to secure these advantages have been an increased wing camber and an increased wing area. However, these expedients are limited by the size of the wings which are capable of being used. Other methods have proposed a wing construction which allows the camber and the wing area to be altered at will. While this latter type of construction is correct in theory, it is nevertheless impractical because of the many mechanical parts required by it.

Besides these practices mentioned above, attempts have been made to increase the lifting power of an airfoil by increasing the air current velocity over the top surface. Along these lines the slotted wing has had considerable success, but as yet it is not suitable in all instances. Also among this latter type of methods for increasing the lift of airfoils, is the use of blowers adapted to direct a stream of air over the upper surface of the plane. These have been unsuccessful due to the fact that a small increase of velocity is obtained for the great amount of weight added to the plane.

It is the major object of this invention to provide a method for increasing the lift of airplanes and means for carrying the same into effect which lack the inherent defects of methods and constructions now in present practice.

An equally important object of the invention is the provision of a method and means for increasing the lift of airfoils independently of the airfoils themselves.

Another object of the invention is the provision of a method for increasing the lift of an airplane comprising revolving a sustain-

ing surface about an axis normally horizontal and perpendicular to the fuselage.

Still another object of the invention is the designing of an impeller adapted to be positioned upon the upper surface of a wing of an airplane and comprising a plurality of blade elements having an airfoil section, the blade elements adapted to be rotated about a horizontal axis.

Yet another object of the invention is the provision of a plurality of groups of sustaining surfaces or impellers adapted to be mounted upon the upper surface of a wing of an airplane on each side of the fuselage, or other parts of the plane, each of the impellers being provided with a plurality of blade elements having an airfoil section, and means mounted upon the airplane, with which the impellers are associated, for rotating them about a horizontal axis so as to increase the lift factor of the completed plane.

A further object of the invention is the designing of an impeller comprising a hub adapted to be mounted upon a rotatable shaft, a plurality of blade elements of an airfoil section being positioned upon the hub.

Still a further object of the invention is the designing of an impeller adapted to be rotated about a horizontal axis and positioned upon the upper surface of a wing of an airplane, the impeller comprising a hub with a plurality of blade elements of an airfoil section positioned thereon, the impeller being fixed upon a rotating shaft which extends through the hub and has its outer end secured to the tips of the blade elements.

With these and other objects in view which may be incident to my improvements, the invention consists in the method and means for carrying the same into effect to be hereinafter set forth and claimed, with the understanding that the necessary steps and the constructions disclosed for carrying them out may be varied without departing from the spirit of the invention or the scope of the appended claims.

The present invention comprehends the provision of a method and apparatus for increasing the lift factor of planes. One manner of practically effecting the concept of the

invention is the provision of a plurality of impellers adapted to be mounted upon the wing of an airplane or other positions thereon, each of the impellers comprising a plurality of blade elements having an airfoil section. The invention also comprehends the rotation of these sustaining surfaces about a horizontal axis so as to increase the lift factor of the airfoil independently of the airfoil itself.

10 In order to make my invention more clearly understood, I have shown in the accompanying drawings, means for carrying the same into practical effect without limiting the improvements in their useful applications to the particular constructions, which, for the purpose of explanation, have been made the subject of illustration.

In the drawings:

20 Figure 1 is a front elevational view of an airplane having the impellers forming the subject matter of the invention associated therewith.

25 Figure 2 is a vertical sectional view along the line 2—2 of Figure 1, and shows a group of blade elements forming each impeller.

Figure 3 is a vertical sectional view on the line 3—3 of Figure 1 looking towards the hub of the impeller.

30 Figure 4 is a longitudinal vertical sectional view showing in detail one of the impellers with its blade elements.

Figure 5 is a perspective view of one of the blade elements of the impeller.

35 Figure 6 is an end view of an impeller looking towards the hub thereof, and shows a different type of mounting for the impellers.

Throughout the drawings similar reference numerals refer to like parts in the different views. There is shown in Figure 1 an airplane having a wing 1, fuselage 2, and a landing gear 3. As may be observed, suitable wing struts 4 are employed for bracing the wing. The fuselage has mounted thereon the usual power source or motor 5 provided with a propeller 6.

40 Adapted to be mounted on the upper surface of the wing 1 are a plurality of impellers or groups of rotatable sustaining surfaces, generally designated by the numeral 7, which form the subject matter of this invention. Each impeller is formed of a plurality of metal blade elements 8 which are secured to a metallic hub 9, in any suitable manner. I have found, however, that the construction disclosed in Figure 4 for securing the blade elements to the hub, will produce very satisfactory and efficient results.

50 60 The hub 9 is, in effect, a hollow cylinder closed at one end by a base. On its inner surface the hub is provided with a flange 10 which extends entirely around the hub and is adapted to cooperate with a groove 11, formed in the base section 12 of each blade

element 8. As may be observed, the base 12 of each blade element is a section of a hollow cylinder, and when positioned as shown in Figure 4, its upper surface is adapted to fit flush with the inner surface of the hub. 70

In order to maintain the blade elements in position a cylindrical keeper 13 is employed. The outer diameter of this keeper is such that when it is placed within the hub, its outer surface will be in bearing with the inner surface of the bases of the blade elements, and will maintain the blade elements in position.

Of course, the keeper 13 may be maintained in the position shown in Figure 4 in any number of ways, such as by welding, by means of bolts passing through the hub, each blade element and the keeper itself, or by suitable keys and keyways therefor. These latter practices have the advantage that the blade elements are detachable. However, any of these means, as well as others not mentioned, may be employed for maintaining the keeper in position, without departing from the spirit of the invention or the scope of the appended claims. 85

It should be noted that the hub is provided at its center with an inwardly projecting flange 14 which has a tapered passage-way adapted to receive the tapered end of a shaft 15 which is securely locked therein by means of a key, not shown, and the nut 16 threaded on the end of the shaft so as to prevent the rotation of the shaft with respect to the impeller hub. However, other means than those disclosed may be employed for securing the hub to the shaft without exceeding the spirit of the invention. 95

It has been previously pointed out that the impellers are mounted upon the upper surface of the wing. In order to accomplish this, suitable bearing mounts 17 are positioned upon the upper surface of the wing and they are adapted to support the shaft 15 of each impeller. The free end of the shaft 15 extends within the housing 18 in which may be mounted a suitable power source for driving the impellers. Housing 18 is suitably streamlined so as to reduce the parasitic resistance of the completed plane. 105

110 It has been mentioned that the impellers are rotated. To accomplish this a power source may be positioned within the housing 18 and may have coupled thereto the ends of the impeller shafts. This construction need not be followed however, as the power source can be positioned within the fuselage of the plane or the impellers may be driven through gearing or other power transmitting mechanism by means of the motor driving the propeller 6. As the invention is not dependent upon the position of the power source adapted to drive the impellers, it has not been shown in the accompanying drawings, in order to simplify them as much as pos- 125 130

sible. Each shaft 15 may be directly connected to its power source, or it may be connected thereto through means of either high or low speed gearing. Also, if desired, a suitable clutch may be positioned between the power source and each shaft 15 so that either or both impellers may be operated at will.

In some instances it may be found desirable 10 to continue the shaft 15 through the hub and outwardly towards the ends of the blade elements. When such a construction is employed a spider 19, shown in Figure 6, may be connected to the shaft and to the blade 15 elements. This type of construction is desirable where the blade elements possess considerable length, as it affords a support for them near their tips.

The hub, blade elements, and keeper are 20 preferably made of metallic construction. Any suitable metal possessing the required compressive and tensile strength factors as well as a light weight or low density, is satisfactory. Another condition desirable in 25 the metal forming the impeller is that it be unaffected by corrosion due to atmospheric and weather conditions. Suitable aluminum alloys fulfill all the conditions set forth above, although any other type of metal now 30 employed in the construction of airplane propellers may be used.

As hereinbefore described, each of the blade elements possess an airfoil section from a point where it joins its base to its tip. 35 The blade elements may be constructed in accordance with any of the well-known practices for forming the blades of metal propellers.

If desired, each impeller may be formed 40 of a single piece of material. For instance a hollow cylinder which is formed of the desired metal may be machined to form the blades and hub and after the elements have been cut to shape they may be buffed and 45 burnished so as to present a smooth surface of the desired form.

It has been mentioned that the blade elements are tapered as to thickness. It may also be observed that their planform, as 50 shown in Figure 5, is also tapered. The airfoil section employed is preferably that shown in Figure 2, where an airfoil section having a concave lower surface is disclosed. By this construction the median line of each 55 airfoil section is substantially that of a circular arc. In either of the constructions shown in Figures 3 and 6, the blade elements are positioned with respect to their hub so that there is a space 20 left between the leading 60 and trailing edges of the adjacent sustaining surfaces. Because of the tapered planform given to each rotating sustaining surface, it may be noted that the spaces 20 between adjacent blade elements, is increased 65 towards the tips of the elements.

Also to be noted is the fact that the blade elements of each impeller are so arranged that the under-surface of each element forms the circumference of a circle having its center at the center of the hub, while the leading edge of any blade element is next to the trailing edge of an adjacent blade element. This arrangement is clearly shown in both Figures 3 and 6. As illustrated in the drawings, blades 8 are so pitched that the leading 70 edge of one blade is spaced from the shaft a distance greater than the trailing edge. This construction permits the leading edge of each block to be acted upon by the air stream.

It has been pointed out as an object of the invention to provide a method and means for increasing the lifting power of airplanes, this increased lift being of particular advantage in allowing a short distance take-off 75 and a relatively low landing speed and small space for landing a plane. As is well known, the creation of lift in an airfoil is due to the pressure differential existing between the pressure upon the upper surface of the airfoil and the pressure upon its lower surface. The pressure upon the upper surface is negative in value, or a suction effect, while that upon the lower surface is positive with respect to the atmospheric pressure. Application 80 of some of the theorems of hydrodynamics, particularly Bernoulli's, are employed to explain the values of these areas of high and low pressure about the airfoil. Dividing the resultant of the force on the airfoil, created by the pressure differential just mentioned, into its components, there is obtained a lift force and a drag force. The 85 value of the lift as well as the drag force changes for various angles of the airfoil with respect to the relative wind or for changes in the angle of attack.

This theory, given above in connection with airfoils functioning as wings for an airplane is now accepted as an explanation for the operation of a propeller or air screw. In the propeller the blades thereof are formed of a plurality of airfoil sections which rotate in a vertical plane at a high 90 velocity.

With the propeller, however, the lift force is in a horizontal plane and is parallel to the axis of rotation of the propeller, while the drag is also in a horizontal plane but is perpendicular to the axis. In a propeller, of course, the lift is called the thrust and it is this force that causes the airplane to be moved forwardly in a horizontal direction. Hence it may be observed, when considering the theory of operation of the propeller as 100 that of a plurality of airfoils, that its thrust is dependent upon a considerable number of factors. One of the most important factors is the blade velocity which determines to a considerable extent, the velocity of the air 105

currents and air stream passing over the airfoils comprising the blades of the propeller.

The purpose of this invention is to combine a propeller construction with that of a wing construction in that, like a propeller the blade elements of the impellers are rotated, and like a wing they are arranged perpendicular to the sides of the fuselage. Moreover, the blade elements, while being rotated are turned in a horizontal plane, while the blades of a propeller are rotated in a vertical plane.

Whatever may be the theory of operation of the impellers, it is the purpose of this invention to combine the operating principles of a wing and those of a propeller so that the best features of both of these devices are obtained with the result that when the impellers are actuated a lift independent of the wing of the plane is created.

In Figure 2 an impeller is shown rotating in a counterclockwise direction with the relative wind directed towards the right as indicated by the arrows. When the blade elements of Figure 2 are in the position shown, air currents will enter the interior of the impeller due to the opening 20 between the leading and trailing edges of adjacent blade elements.

Upon entering the opening or space 20, the air is suddenly restricted so that an increase in velocity results. Immediately upon passing through the passageway, and entering into the impeller so that it is adjacent the under-surface of the blade elements, the velocity is reduced due to the release of the air from its confinement by the passage between the blade elements through which it passes. The result of the reduction of velocity of the air stream passing through the impeller causes an increase in its pressure which creates a pressure differential between the outer and inner surfaces of the blade elements. The air stream encircled by the impeller blades, having entered at the left, passes outwardly from the interior of the impeller in a path of least resistance.

The impellers are rotated at a considerable speed and consequently each blade element attains a high velocity. Each blade element, therefore, rotates a great many times for any given period, taken as a unit, and the resultant lift of the impeller will remain substantially constant. The impellers are rotated at any suitable speed which it determined by the conditions which must be met.

When it is desired to take off, the motor 5 is actuated so as to rotate the propeller 6, and the impellers are also rotated. Due to the rotation of the impellers, an independent lift is created besides that of the wing of the airplane itself, with the result that the airplane may take off in a small area. The plane having attained altitude, the actuation of the impellers may be arrested or main-

tained as desired. When it is desired to land the plane, the impellers are rotated so as to obtain their lift, and the plane is landed in the usual manner but with the advantage that a decrease in area required to land it is obtained.

The impellers may or may not be actuated while the ship is flying. Because of the increased lift obtained by them they are of considerable advantage in obtaining altitude and in climbing. As the impellers may be associated with any type of plane by merely mounting them upon a wing or other part of the plane, it is apparent that they will increase the "ceiling" which the ship may obtain.

It is also apparent that the impellers may be utilized for stabilizing an airplane with which they are associated and are of considerable benefit in pulling the airplane out of spins, rolls, or dives, as they may either be actuated together or independently.

It has been found by experiment that when a device constructed in accordance with the present invention is placed in operation, that there is produced a movement in a horizontal direction as well as the lift effect hereinbefore described. For instance, when a structure is provided with the rotary impellers, there is a decided force exerted in a horizontal direction which is effected for producing movement in a horizontal direction. Thus, it is possible that impellers constructed in accordance with the present invention may be employed for moving an airplane equipped with the same in a horizontal direction as well as tending to increase the lift. It, of course, is obvious that the impellers may be arranged in positions other than that shown in the drawings to obtain the full benefit of the force produced in the horizontal plane by the impellers.

While each impeller has been shown as composed of three blade elements, it is obvious that more may be employed, if desired. In connection with the length and the width of each blade element, or its aspect ratio, it may be observed that this may be varied at will, and is determined by the particular results sought to be attained. Similarly the thickness of the airfoil section or its maximum ordinate is determined by the special conditions which the impellers are required to meet. By the use of the spider construction shown in Figure 6, the length of the blade elements and consequently the area, may be increased. If desired, the shaft 15 may extend beyond the tips of each blade element and its outer end may be supported upon an upright bearing similar to that designated by the reference numeral 17.

Although the blade elements have been disclosed as associated with a monoplane, it is to be understood that the invention is in no ways limited to that type of airship. Ob-

viously, the impellers could be associated with a multi-wing plane, and could be positioned upon each wing or upon the upper wing only. In all instances, wherever the impellers are employed, they are positioned at such a distance from a wing (or wings in the case of a multi-wing plane) that they do not interfere with the air currents passing adjacent the wing. Of course, in any instance the blades 10 are so arranged relative to the rotation of the impeller and the direction of movement of the air stream as to exert a desirable effect. It may be found advantageous to construct 15 the impeller blades so that the assembled impeller is of a larger diameter at the blade tips than at the hub.

Having described the features and operation of the device, it will be appreciated from the foregoing description that I have provided 20 a method and means for greatly increasing the lifting powers of airfoils. Such construction as that disclosed will allow a short distance take off for a plane and a relatively small landing area besides having 25 many other advantageous effects which result from the benefit of increasing the lift of airfoils.

While I have shown and described the preferred embodiment of my invention, I wish 30 it to be understood that I do not confine myself to the precise means herein set forth for performing the method outlined above, as it is apparent that many changes and variations may be made therein, by those skilled 35 in the art, without departing from the spirit of the invention or exceeding the scope of the appended claims.

I claim:

1. An impeller for an airplane adapted to 40 be associated with a wing thereof, said impeller comprising a hub having a plurality of blade elements having an airfoil section positioned thereon in substantially cylindrical formation, the leading edge of one blade being 45 closely positioned with respect to the trailing edge of an adjacent blade so as to form a restricted opening between adjacent blades, the leading edges of the blades being positioned a greater distance from the axis 50 of the cylinder formed by the blades than the trailing edges, said blade elements adapted to be rotated about a horizontal axis.

2. An impeller adapted to be associated 55 with a wing of an airplane for increasing the lift of said plane, said impeller comprising a cylindrical hub closed at one end, a plurality of blade elements having base portions adapted to sit flush within said hub, and a keeper positioned within said hub for maintaining the blade elements on the hub, said hub being mounted upon a shaft adapted to be rotated.

3. An impeller adapted to be associated 60 with a wing of an airplane for increasing the lift of said plane, said impeller comprising

ing a cylindrical hub closed at one end, a plurality of blade elements of an airfoil section having base portions adapted to sit flush with said hub, and a keeper positioned concentrically within said hub for maintaining 70 the blade elements on the hub, said hub being mounted upon a shaft adapted to be rotated.

4. An impeller adapted to increase the lift of an airplane, said impeller comprising a 75 hollow cylindrical hub having a closed end, a circular flange formed within said hub, blade elements having semi-annular base portions positioned within said hub, the base of each blade element being provided with 80 a groove adapted to cooperate with said flange, and a keeper member positioned within the annulus formed by the assembled blade elements for maintaining the blade elements in position, said impeller adapted to 85 be mounted upon the upper surface of the wing of the airplane and to be rotated about a horizontal axis.

5. An impeller adapted to increase the lift of an airplane, said impeller comprising a 90 hollow cylindrical hub having a closed end, a circular flange formed within said hub, blade elements having an airfoil section positioned within said hub, the base of each blade element being provided with a groove adapted 95 to cooperate with said flange, and a keeper member positioned concentrically within the assembled blade elements for maintaining the blade elements in position, said impeller adapted to be mounted upon the upper surface of the wing of the airplane and to be rotated about 100 a horizontal axis.

6. An impeller adapted to be associated with an airplane for increasing the lift thereof, said impeller comprising a hub, a plurality of blade elements secured thereto in substantially cylindrical formation, the leading edge of one blade being closely positioned with respect to the trailing edge of an adjacent blade so as to form a restricted opening 110 between adjacent blades, the leading edges of the blades being positioned a greater distance from the axis of the cylinder formed by the blades than the trailing edges, each of 115 said blade elements having an airfoil section and formed with a tapered planform, said blade elements adapted to be rotated about a horizontal axis.

7. An impeller for an airplane adapted to increase the lift thereof, said impeller comprising a cylindrical-like hub having a closed end, a plurality of blade elements having an airfoil section mounted upon said hub in spaced apart relationship with respect to each other, said elements being so positioned that 120 the leading and trailing edges of any two of them are adjacent each other, said hub adapted to be mounted upon a rotatable shaft so that the blade elements may be rotated about 125 a horizontal axis.

8. In an airplane an impeller mounted upon each semi-span of a wing, each of said impellers comprising a hub and a plurality of fixed blade elements associated therewith, said blade elements being so positioned as to form a substantially cylindrical surface, said hub being mounted upon a rotatable shaft perpendicular to the fuselage of the plane, and means for rotating said shaft so as to 5 actuate the impellers, said blades also being positioned so that the leading edges thereof are positioned from the axis of the cylinder a greater distance than the trailing edges thereof.
9. In an airplane having an impeller mounted upon each semi-span of a wing, each of said impellers comprising a single hub, a plurality of blade elements having an airfoil section positioned upon said hub in spaced 10 apart relationship with respect to each other in cylindrical formation, the leading and trailing edges of two adjacent blade elements being adjacent each other so as to form a restricted opening between adjacent blades,
- 25 the hub of each impeller being mounted upon a rotatable shaft parallel with the longitudinal axis of the wing and perpendicular to the transverse axis of the wing, and means for rotating said impeller.
- 30 10. An apparatus for propelling and increasing the lift of an airplane comprising an impeller mounted upon each semi-span of a wing, each of said impellers comprising a hub and a plurality of fixed blade elements associated therewith in substantially cylindrical formation, the leading edge of one blade being closely positioned with respect to the trailing edge of an adjacent blade so as to form a restricted opening between adjacent blades, the leading edges of the blades being positioned a greater distance from the axis of the cylinder formed by the blades than the trailing edges, said hub being mounted upon a rotatable shaft perpendicular to the fuselage of the plane, and means for rotating said shaft so as to actuate the impellers.
- 35 11. An airplane consisting of a body portion, a wing structure associated therewith, means for propelling the airplane through the air, means mounted on each semi-span of the wing comprising an impeller adapted to increase the lift thereof, said impeller comprising a cylindrical-like hub having a closed 40 end, a plurality of blade elements having an airfoil section mounted upon said hub in spaced apart relationship with respect to each other, said elements being so positioned that the leading and trailing edges of any two of them are adjacent each other, said hub adapted to be mounted upon a rotatable shaft so that the blade elements may be rotated about a horizontal axis.

In testimony whereof I affix my signature.
TRIAN BERBECK.
